UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

LINE-SWITCH SYSTEM.

1,382,012.

Specification of Letters Patent. Patented June 21, 1921.

Application filed May 14, 1919. Serial No. 297,086.

To all whom it may concern:

Be it known that I, WINFRED T. POWELL, a citizen of the United States, residing at Rochester, in the county of Monroe and State of New York, have invented certain new and useful Improvements in Line-Switch Systems, of which the following is a full, clear, concise, and exact description.

This invention relates to telephone systems, and more particularly to telephone systems employing automatic switches for completing connections between calling and called subscribers.

The present invention has for its purpose the improvement in the operating circuits of distributor switches of the type which have no normal or "home" position; that is, the distributor switch is not restored to normal position or disconnection, but remains in engagement with the trunk or line last used.

One feature of the invention relates to the arrangement whereby the line switch associated with the called line is prevented from seizing the trunk with which it happens to be in engagement when its associated line is called. Other features not specifically enumerated will appear from the detailed description and claims.

The figure of the drawing diagrammatically represents a portion of a telephone system in which the portion of the drawing appearing at the left of the dotted line represents a calling substation and line, together with the operating circuits of a line of distributor switch. The portion of the drawing included between the two dotted lines diagrammatically represents the operating circuits of a connector switch, while that portion of the drawing appearing at the right of the dotted line represents the operating circuits of the distributor or line switch individual to the called line and also shows the called substation circuits.

The line or distributing switch which will be referred to in the detailed description, comprises a flat rotary switch in which there are four series of contacts arranged to form an arcuate bank. Four brushes are provided, each one of these brushes coöperating with one of the four series of contacts. These brushes are rotated by a stepping magnet but are not restored to normal or disconnection, since they remain in engage-

ment with the trunk last used until the line with which they are associated becomes engaged as a called line. At that time the brushes of the switch are moved out of engagement with its fixed contacts or terminals, into a position between these contacts. This is accomplished as follows: The brushes of the switch which are designated 2, 6, 11 and 12, are fixed to a rotatable shaft which is provided with a ratchet wheel 32, arranged to be driven in one direction only. This ratchet wheel is engaged by two pawls 33 and 34, carried by the armature of the motor magnet MM. The brushes of the line switch are so arranged with respect to the line contacts or terminals, that when the motor magnet MM is energized and deenergized, the paws 33 and 34 will move the switch brushes from one set of contacts to the next set of contacts in the series. It will thus be seen that when the motor magnet MM is energized, the line switch brushes will be advanced to a position intermediate of the sets of contacts.

The connector switch which will be referred to in the description may be of the type substantially the same as that shown in the patent to Keith *et al.*, 815,176, issued Mar. 13th, 1906.

It is believed that the invention will best be understood by describing the operation of establishing a connection from the calling substation at A, to the called subscriber's station at B. When the calling subscriber at A removes his receiver from its switchhook, the line relay LR is energized over a circuit extending from grounded battery, winding of this relay, inner back contact and armature of cut-off relay CO, through the calling subscriber's line and sub-station circuits, upper armature and back contact of the cut-off relay, to ground. At its left hand armature and contact spring, a guarding potential is applied to the test contacts of the calling line appearing at various connectors. The circuit for applying this guarding potential is traced from ground, through the line switch brush 2, left hand spring and armature of the line relay, conductor 3 to the multiple test terminals of the calling line at various connectors. At the right hand armature and front contact of the line relay an operating circuit for the motor magnet MM is com-

pleted from grounded battery, winding of this magnet, through its self-interrupting contact springs 4, conductor 8, lower back contact and armature of the cut-off relay 5 CO, right hand armature and front contact of the line relay, through the test brush 6 of the line switch and over the test conductor of busy trunks to ground at the left hand front contact and armature of the 10 slow releasing relay 7 at various busy connector switches.

The motor magnet MM continues to advance the line switch over circuits similar to that just described until an idle trunk is 15 reached where an idle condition is indicated by reduced potential on its test terminal. As soon as the idle trunk is seized, cut-off relay CO is operated over a circuit completed from grounded battery, winding of 20 motor magnet MM, conductor 8, winding of the cut-off relay, left hand contact spring and armature of the line relay LR to ground over line brush 2. Prior to this time the cut-off relay had been short-circuited by a 25 path traced from grounded battery, winding of the motor magnet MM, self-interrupting springs 4, conductor 5, lower back contact and armature of the cut-off relay, right hand armature and front contact of the line 30 relay LR, to ground over test brush 6, and the test terminals of busy trunks. The cut-off relay CO, upon energization attracts its armatures, and at its upper armatures extends the conductors of the calling line to the 35 conductors of the selected trunk, and also interrupts the energizing circuit of the line relay LR, causing this relay to retract its armatures. At the lower armature and front contact of the cut-off relay, this relay 40 completes a locking circuit for itself from ground applied to conductor 9, either at the left hand armature and front contact of the slow releasing relay 7, or at contact 10 of the off normal switch at the connector, line 45 switch test brush 6, lower front contact and armature of the cut-off relay, back contact and spring of the line relay LR, winding of the cut-off relay CO, conductor 8, winding of the motor magnet MM, to grounded battery. The apparatus is now in condition to 50 receive the impulses from the calling subscriber's dial switch. The motor magnet, such as MM of the line switch is so designed that it will not operate in series with the 55 cut-off relay, such as CO, but when the motor magnet is once energized it will remain operated in series with the cut-off relay.

In this disclosure it is not deemed necessary to disclose the operating circuits of the 60 selector switch, although it will be readily understood how the line switch circuits of this invention will coöperate with such selector switch circuits. Inasmuch as the only numerical switch disclosed, is a connector, 65 it will be necessary for the calling subscriber

to transmit only two series of impulses, one corresponding to the tens digit, and the other to the units digit of the wanted number. As soon as the calling line was extended to an idle connector, the stepping relay SR of that 70 connector, is energized over a circuit completed from grounded battery, winding of this relay, line switch brush 11, inner front contact and armature of the cut-off relay CO, through the calling subscriber's line and substation circuits, upper armature and front contact of the cut-off relay, line switch brush 12, winding of the impedance coil 13, to ground. On the first energization of the stepping relay SR, the slow releasing relay 80 is energized. In response to the tens series of impulses, the stepping relay SR vibrates its armature, but since the relay 7 is slow to release, it will not be deenergized during 85 momentary interruptions of its energizing circuit. On each retraction of the armature of the stepping relay SR, an energizing circuit is completed for the primary motor magnet PM, which moves the connector switch through its primary or groups selecting movement. This energizing circuit is traced from grounded battery, winding of the primary motor magnet PM, side switch wiper 14 in its first position, slow releasing relay 15, right hand front contact and armature of the slow releasing relay 7, back contact and armature of the stepping relay SR, 90 to ground.

On the first completion of this circuit, the slow releasing relay 15 is energized and does 100 not deenergize until the close of the series of impulses. When the relay 15 attracts its armature, an operating circuit for the escape magnet TSC is closed from grounded battery, resistance, winding of the escape 105 magnet, the spring and armature of the relay 15, to ground. At the close of the tens series of impulses, the stepping relay SR attracts its armature for a relatively long interval, so that the slow releasing relay 15 110 deenergizes to interrupt the operating circuit of the escape magnet. This magnet, as is well known, operates on deenergization to move the side switch wipers into a succeeding position, in this instance its second position.

When now the subscriber transmits impulses corresponding to the units digit of the wanted number, the stepping relay SR will again vibrate its armature, but in this instance will complete an operating circuit for the secondary motor magnet SM, from grounded battery, winding of this magnet, lower armature and back contact of the test relay 16, side switch wiper 14 in its second 125 position, slow releasing relay 15, right hand front contact and armature of the relay 7, back contact and armature of the relay SR, to ground. The magnet SM and the relay 15 are energized in this circuit, the relay 130

15 operating to complete the energizing circuit for the escape magnet as previously described. The motor magnet SM operates as is well known to advance the connector 5 switch in a secondary direction to select the wanted line from the previously selected group of lines.

At the close of the units series of impulses, 10 the connector switch is in operative relation to the connector terminals of the wanted subscriber's line, so that if the wanted line is idle the connection may proceed, as follows: Since there is no guarding potential on the test terminals 17 of the wanted line, the 15 escape magnet ESC will be deenergized at the close of the units series of impulses and will now move the side switch wipers such as 14, 22, 25, 26 and 27 into their third, or ringing position. In this position the called 20 subscriber is signaled by ringing current supplied over a circuit from grounded battery, ringing generator 18, interrupter 19, lamp 20, ringing trip relay 21, side switch wiper 22 in its third position, connector brush 23, through the bell at the called subscriber's substation, back to connector brush 24, side switch wiper 25, to ground. In the 25 third position of the side switch wipers, a circuit is also completed for the escape magnet brush 23, through the bell at the called subscriber's substation, back to connector brush 24, side switch wiper 25, to ground. The escape magnet remains energized until the called subscriber 30 responds by removing his receiver from its switchhook, whereupon the marginal trip relay 21 receives sufficient current to attract its armature. The escape magnet is then short-circuited at the front contact and armature of the trip relay 21, and the side switch wipers are moved into their fourth, or talking position. In this position of the 35 side switch wipers, a telephonic circuit is completed; the talking battery for the calling subscriber being supplied through the winding of the stepping magnet SR and impedance coil 13, while the talking battery for the called subscriber is supplied through the winding of the impedance coil 14. A 40 guarding potential for the called line is supplied through the side switch wiper 27 in its third or fourth positions.

If the called line had been busy at the 45 close of the units series of impulses when the connector switch brushes were placed in engagement with this line, the escape magnet would have been held energized over a circuit traced from grounded battery, resistance, winding of the escape magnet, make- 50 before-break contact and spring at relay 15, winding of the test relay 16, spring and contact 29 at this relay, side switch wiper 27 in its second position, test brush 30, test terminal 17, to ground at side switch wipers 27 at 55 another connector switch. The test relay 16

is energized in this circuit and attracts its armature to complete a locking circuit for itself, from spring and inner armature of the test relay, contact 30', and off normal spring, to ground. At the upper armature 70 of the test relay, a circuit is closed for applying of a busy tone from the busy machine BZ to the calling subscriber.

When the calling subscriber desires to dis-establish the connection, either because the 75 wanted line is busy or because the conversation is completed, he replaces his receiver on its switchhook. This causes the stepping relay SR to deenergize, and after a short interval of time, the slow release relay 7 also 80 deenergizes. A circuit is thereupon completed for the release magnet from grounded battery, winding of the release magnet REL, off normal spring and contact 31, right hand back contacts and armatures of the relays 7 85 and SR, to ground. When the slow releasing relay 7 retracted its armatures, the holding ground for the cut-off relay CO was removed, and the cut-off relay deenergized to re-connect the line relay LR to the calling 90 subscriber's line. Since the line switch has no normal position, these brushes remain in engagement with the contacts or terminals of the trunk last used.

It has been found that when line switches 95 of this character have been employed, that means must be provided to prevent the line switch associated with the called line from selecting a trunk whenever the called line is seized. In accordance with the present invention whenever a line is selected as a called line, such as B, the motor magnet M'M' is energized over a circuit extending from grounded battery, and back contact and armature of the motor magnet M'M' and later the resistance extending around this contact and armature, lower armature and back contact of the cut-off relay C'O', continuity contacts of the line relay L'R', test terminal 17, test brush 30, side switch 100 wiper 27 in its third or fourth positions, to ground. Subsequently the motor magnet M'M' and cut-off relay C'O' are energized in series over conductor 34 and test terminal 17. The motor magnet M'M' is thus held 105 energized during the conversation, and thereby holds the brushes of its associated line switch out of engagement with its trunk terminals, so that a trunk will not be seized by this switch at this time. When the called 110 line is no longer busy its cut-off relay and motor magnet deenergize and the magnet advances the associated finder brushes into engagement with some trunk terminals.

It will be noted that when a line is seized 115 by a connector switch, the ground on the test wire operates the stepping magnet of the called line switch to move and hold the brushes or wipers of this switch between the contacts or terminals of its contact bank. 130

After the brushes or wipers of the line switch have moved away from engagement with the contacts of the contact bank it is then necessary to operate the cut-off relay 5 C'O', but this cut-off relay is short-circuited by the contacts of the stepping magnet when the contacts of the motor magnet M'M' are closed. When the contacts of the stepping magnet are open, the cut-off relay C'O' is in 10 series with the stepping magnet and without the resistance across the contacts of the stepping magnet, the sudden rush of current through the cut-off relay in series with the stepping or motor magnet would cause a 15 surge of current in the stepping magnet in the opposite direction from the current which originally operated it, with the result that the stepping magnet might release. However, with the resistance coil about the 20 contacts of the stepping magnet placed in parallel with the cut-off relay until this relay operates, the mentioned surge of current is shunted through the resistance coil and thus does not affect the stepping magnet. 25 While the circuits of the present invention have been employed in connection with a line switch, it will be understood that they may be used equally well in operating a distributor switch, such as is employed in ap- 30 portioning calls to operators in call distributing systems. In the present disclosure only line and connector switch circuits are shown, but it will be readily understood that if the present invention is employed in 35 a larger system, that the line switch circuits will coöperate with selector switches as well as with connector switch circuits.

What I claim is:

1. In a telephone system, telephone lines, connector switches having contacts in which said lines terminate, a line switch provided with fixed and movable contacts having no normal position, each of the said telephone lines terminating in the movable contacts of 45 one of said line switches, means for connecting with any line through one of the said connector switches, and means effective thereupon for moving said movable contacts of the associated line switch out of engagement with its fixed contacts.
2. In a telephone system, telephone lines, connector switches having contacts in which said lines terminate, a line switch provided with fixed and movable contacts having no 55 normal position, each of the said telephone lines terminating in the movable contacts of one of said line switches, means for connecting with any line through one of the said connector switches, and means effective thereupon for moving said movable contacts of the associated line switch out of engagement with its fixed contacts to a position intermediate of said contacts.
3. In a telephone system, a plurality of 65 telephone lines, a connector switch in which

the said lines terminate, a line switch individual to each line having no normal position, outgoing lines terminating in each line switch, means for causing a connector switch to seize one of said telephone lines, and means then effective for causing the line switch individual to the selected telephone line to move out of engagement with all of said outgoing lines. 70

4. In a telephone system, a telephone line, 75 means for seizing said line as a called line, a line switch individual to said line, outgoing lines at said switch with some one of which said line switch is normally in engagement, and means operative when the telephone line is seized as a called line to move said line switch out of engagement with said outgoing lines. 80

5. In a telephone system, a telephone line arranged to function as a calling and a 85 called line, a line switch individual to said line, outgoing lines at the said switch with some line of which said switch is normally in engagement, operating means for said switch having two circuits, one for advancing 90 the switch to select an idle outgoing line, and the other to move said switch out of engagement with any of said outgoing lines, when the telephone line is seized as a called line. 95

6. In a telephone system, a telephone line, means for seizing said line as a called line, a line switch individual to said line, outgoing lines terminating at said switch with some one of which said line switch is normally in engagement, and a motor magnet for advancing said switch, said motor magnet having two circuits, one for advancing the switch to select an idle outgoing line, and the other to move said switch out of engagement with any of said outgoing lines. 100

7. In a telephone system, a telephone line, means for seizing said line as a called line, a line switch individual to said line, outgoing lines at said switch with some one of which said line switch is normally in engagement, a cut-off relay and a motor magnet associated with said line switch, and a circuit including said motor magnet and cut-off relay having two branches, one completed 110 when the line is calling, and the other branch completed when the line is seized as a called line. 115

8. In a telephone system, a telephone line, means for seizing said line as a called line, 120 a line switch individual to said line, outgoing lines at said switch with some one of which said line switch is normally in engagement, a cut-off relay and a motor magnet associated with said line switch, and a 125 circuit including said motor magnet and cut-off relay having two branches, one completed when the line is calling, and the other branch completed when the line is seized as a called line, said motor magnet being energized 130

when one branch of the circuit is completed and deenergized when the other branch is completed.

9. In a telephone system, a plurality of 5 telephone lines, a line switch individual to each line, trunk lines terminating in said switch, a motor magnet operating on energization and deenergization to cause said switch to move from one trunk line to the 10 next succeeding trunk line, mechanism for seizing any one of said lines as a called line, and means operative thereupon for maintaining energized the motor magnet of the line switch associated with the selected line.

15 10. In a telephone system, a plurality of telephone lines, a line switch individual to each line, trunk lines terminating in said switch, a motor magnet operating on energization to move said switch between two 20 adjacent trunks on each energization and on deenergization into engagement with the next succeeding trunk, mechanism for seizing one of said lines as a called line, and means operative thereupon for maintaining 25 energized the motor magnet of the line switch associated with the called line.

11. In a telephone system, a plurality of telephone lines, a line switch individual to each line, trunk lines terminating in each of 30 said line switches, a motor magnet operating on energization to move said switch out of engagement with any of said trunks and operating on deenergization to cause said switch to engage one of said trunks, means for seizing 35 any of said lines as a called line, and means operative thereupon for maintaining

energized the cut-off relay and motor magnet associated with the called line.

12. In a telephone system, a plurality of 40 lines, an individual line switch for each line, provided with brushes and with fixed contacts, outgoing circuits multiply connected to said fixed contacts, means for normally maintaining said line switches in engagement with the contacts of some outgoing circuits 45 and means for moving a line switch from a set of fixed contacts as soon as the line of said last mentioned line switch is seized as a called line.

13. In a telephone system, a plurality of 50 telephone lines, an individual line switch for each line, outgoing circuits multiply connected to said line switches, means for maintaining each line switch in an engagement with some outgoing circuit and means for 55 moving the line switch of a called line from the outgoing circuit with which said last mentioned switch is in engagement when said called line is seized.

14. In a telephone system, a plurality of 60 telephone lines, a line switch for each line provided with line contacts and trunk contacts, trunk circuits multiply connected to said trunk contacts, means for maintaining said line contacts in engagement with some 65 one of said trunk contacts and means for moving the line contacts of a called line switch from the trunk contacts with which it is in engagement.

In witness whereof, I hereunto subscribe 70 my name this 13th day of May, A. D. 1919.

WINFRED T. POWELL
